UNITED STATES PATENT OFFICE,

WILLIAM H. PEPPER AND ALBERT T. L. DAVIS, OF LAKE VILLAGE, ASSIGNEES TO THE PITMAN MANUFACTURING COMPANY, OF LACONIA, NEW HAMPSHIRE.

SPLICING-THREAD GRIPPER AND SLACKENER FOR KNITTING-MACHINES.

SPECIFICATION forming part of Letters Patent No. 443,462, dated December 23, 1890.

Application filed February 5, 1890. Serial No. 339,297. (No model.)

To all whom it may concern:

Be it known that we, WILLIAM H. PEPPER and ALBERT T. L. DAVIS, of Lake Village, in the county of Belknap and State of New Hampshire, have invented certain new and useful Improvements in Splicing-Thread Gripers and Slackeners for Knitting-Machines, of which the following is a specification.

The present invention relates to the formation of a re-enforced or spliced section or "patch" in knitted fabrics in order to strengthen the same in any desired portion, as, for example, in forming a section or patch of double thickness at the knee of a knitted stocking. Such re-enforced sections are usually formed during the knitting of the fabric by running in an extra or splicing thread at the proper place and knitting the desired portion with this splicing-thread, in addition to the usual or main thread or threads. Since in the class of fabrics to the formation of which the present invention relates it is desirable that the re-enforced section or patch should occupy only a portion of the breadth of the fabric, (or of the periphery thereof in the case of a circular web,) it is usual to feed or run in the splicing-thread at a predetermined point at each round of the knitting and to break it off at another predetermined point, so that the completed patch is made up of a plurality of separate splicing-threads knit in succession into the fabric. In feeding in the splicing-thread (or threads, if each spliced thread in the completed fabric is to be regarded as a separate thread) it is essential that it should always be fed in exactly at the proper point, in order to render the patch regular and of good appearance; that it should be fed in with certainty, in order that there should be no omitted splicing-threads in the completed patch, and that the feeding in should be effected by a minimum of mechanical contrivances.

One of the methods which has hitherto been adopted for feeding in the splicing-thread has been to pass both the main thread and the splicing-thread through the same thread-guide on the machine-head, whereby the splicing-thread is fed in by frictional contact therewith of the main thread, and in order

that the splicing-thread may be fed or put in invariably at the proper point, irrespective of the smoothness of the thread or of increases of tension upon the splicing-thread, it has been proposed to entirely relieve the splicing-thread of all tension at the moment when its end is to be fed into the needles, so that the frictional contact therewith of the main thread will feed it in, there thus being no strain to be overcome by the main thread. The tension upon the feeding-in end of the splicing-thread is relieved in these machines by slackening the splicing-thread, so that the splicing-thread hangs loose and entirely free from tension.

Now the present invention relates to splicing-machines of this general character, wherein the splicing-thread is fed in by the frictional contact therewith of the main thread, and wherein the splicing-thread is relieved of all tension and is slackened when it is first fed in; and the present invention consists in improvements in the mechanism of such machines, which are simple in construction, certain in operation, and which can be added to nearly all types of ordinary circular-knitting machines to render them capable of knitting in splicing-threads when desired.

In the accompanying drawings the improved mechanism is shown as applied to a circular-knitting machine of a well-known type for forming a ribbed circular web.

In the drawings, Figure 1 is a side view of the head of a knitting-machine having the improvements applied thereto. Fig. 2 is a plan thereof, the splicing-thread-bobbin support and its adjuncts being removed; and Figs. 3, 4, 5, 6, 7, 8, and 9 are views of parts in detail.

A is the usual head-plate of a knitting-machine which supports the knitting mechanism.

B is the constantly-rotating cylinder or ring which operates the cylinder-needles.

C is the stationary needle-cylinder.

D is the stationary dial-needle plate, and E is the constantly-rotating dial cam-plate which actuates the dial-needles and which is rigidly connected with the cylinder or ring C by means of a spindle *a* and arm *b*.

The thread-guide plate F is secured by a bracket-arm G to the cam-plate E, so as to rotate therewith, and is provided with a single leading-in thread-guide eye c, (see Figs. 4 and 5,) through which both the main thread x and the splicing-thread y pass.

The splicing-thread bobbin II is carried by a bracket I, centrally supported on the rotating spindle a, so that the bobbin turns with the 10 thread-guide. To the bracket I is secured a vertical post d, having a horizontally-extending tension-bar e, suitably bent or notched at f to constitute a thread-guide, and carrying an outwardly-projecting arm g, (preferably a 15 spring-arm,) having on its outer extremity a tension thread-eye h. The splicing-thread passes upwardly from its bobbin over the bar e in the guide-notch f, and thence through the tension-eye h downwardly to the leading- 20 in thread-guide eye c in the thread-guide plate F. The proper tension to the splicing-thread is given by the friction caused by its passing over the notch f and through the tension-eye h, and also by the elasticity of 25 the spring-arm g, which are sufficient to cause the splicing-thread to be knit properly. The main thread x is led from its bobbin (which may be located at any convenient place) through tension and-guide eyes i i on the 30 post d, and the bracket-arm G to the leading-in thread-guide eye c, through which both the main and the splicing threads are guided and led to the needles.

In describing the mechanisms and operations involved in feeding in the splicing-thread and in breaking off the thread on each 35 round of stitches the latter will be first described, since an understanding thereof is prerequisite to a clear comprehension of the 40 feeding-in operation and mechanism. In passing from the upper tension thread-eye h to the leading-in thread-guide eye c, which lays the threads onto the needles, the splicing-thread passes between a stationary gripping-jaw j, carried by the guide-plate F, and a movable gripping-jaw J, which is capable of moving to and from the gripping-jaw j, and is held and guided in suitable ways formed in the bracket-arm G. A proper guide, as a 45 curved bar l, is provided in the vicinity of the gripper formed by the two gripping-jaws, so that the splicing-thread must necessarily always pass between the movable and the fixed gripping-jaws. This curved bar, however, is normally out of contact with the splicing-thread, so that no tension on the thread is due thereto. When the movable gripping-jaw is moved out of contact with the fixed jaw, the splicing-thread is free to be fed to 50 the needles. When, however, the gripping-jaws come together, the splicing-thread is thereby firmly gripped and its further feeding in is prevented. If, then, the needles have been operating upon the splicing-thread, 55 when the splicing-thread is gripped by the gripper, it is broken off by the continued movement of the cam-plate E, which carries

the thread-guide plate, the gripper, and the bobbin of the splicing-thread, and as long as the gripper holds the splicing-thread the 70 splicing-thread cannot be fed in to the needles. The gripping of the splicing-thread, therefore, by the gripper determines the point in each round where the splicing-thread is broken and where the patch terminates, and the release of the splicing-thread by the gripper is prerequisite to enable the splicing-thread to be fed to the needles.

During the knitting of the unspliced portions of the web the gripper always holds the 80 splicing-thread, so that in the normal position of the gripper the splicing-thread is inactive. The gripper is primarily brought into operation by means of a pattern-chain K, operated in a usual manner, and having 85 at proper intervals cams m (which initiate the splicing operation) and cams n, (which discontinue the splicing operation.) The cams m and n occupy different planes on the pattern-chain. The number and relative positions of the cams m n on the pattern-chain are determined by the character of the work to be done, and as such a pattern-chain is in itself old and well known only one cam m and one cam n are shown. The pattern-cams m 90 n co-operate, respectively, with two vertically-movable rods L M, guided in suitable ways formed in a bracket N, fixed to the head-plate A. The pattern-cams lift the rods, and when the cams have passed the rods drop by 95 gravity, their downward movement being limited by guide-pins o o, working in suitable guide-slots, said guide-pins also preventing any rotation of the rods in their respective ways.

Pivoted at p to the upper face of the bracket N is a horizontally-swinging lever P, co-acting with both rods L and M, its pivotal point being located between the said rods, so that when the inner rod M is raised it will swing 100 the lever in the direction indicated by the arrow 2, and when the outer rod L is raised it will be swung in the opposite direction. The coacting faces of the rods L and M and of the lever P are properly beveled (see Fig. 105 3) to render their movements easy. Whenever moved to either position by one of the rods the lever remains there until acted upon by the other rod.

Alongside the lever P, and pivoted to the 110 outer end of the bracket N, on its side, is a vertically-swinging lever Q, the free end of which is held from lateral displacement and the downward movement thereof limited by proper guides on or in the bracket N. This 115 lever Q is acted upon by the lever P in such manner that it is lifted by said lever P when the latter is moved by the outer rod L. This is conveniently accomplished by a beveled or cam-shaped projecting tongue q on the inner 120 end of the horizontally-swinging lever P, which registers with an aperture r in the vertically-swinging lever Q. When the lever P is operated by the outer rod L, its tongue en-

ters the aperture r , and the cam-face of the tongue, engaging the upper margin of said aperture, raises the free end of the lever Q. The lever Q remains in this elevated position 5 until the lever P is acted upon by the inner rod M, which swings lever P, so as to disengage its cam-tongue from the aperture in lever Q, which latter then resumes by gravity its normal lower position.

10 The lever Q carries on its lower end a gripper-actuating cam-plate R, the essential characteristic of which is that its forward edge is nearer the axis of the needle-actuating cylinder and dial-plate than its rear edge. When 15 the lever Q is raised, this gripper-actuating cam-plate is brought into the path of a rotating part which is in operative connection with the movable splicing-thread-gripping jaw J, and the cam-plate remains in this 20 operative position until the lever Q resumes its normal position after the completion of the spliced section or patch. The essential operation, therefore, of the mechanism between the pattern-chain and the gripper-actuating 25 cam-plate is such that the said cam-plate is brought into operative position when the formation of the patch is to be initiated, remains in this operative position during the entire formation of the patch, and resumes 30 its normal inactive position on the completion of the patch.

The movable gripping-jaw J is acted upon directly by a horizontal radial reciprocating cam-bar S, which slides in a radial horizontal line in suitable ways formed in or on the bracket-arm G, the movement of the cam-bar in either direction being limited by stop-pins s s, which engage the bracket-arm. The gripping-jaw J is formed on one side with a horizontally-extending open recess or notch t, the vertical extent of which is equal to the vertical thickness of the co-operating portions of the cam-bar which fits and slides in this horizontal recess or notch. The cam-bar (see 45 Fig. 6) has an inclined cam-face u on its upper surface and an inclined cam-face v on its lower surface. When the cam-bar is drawn out—that is, when it is moved radially away from the axis of the machine—its upper cam-face u engages the upper margin of the notch t in the movable gripping-jaw, thus raising it, and when the cam-bar is moved inwardly its lower cam-face v engages the lower margin of the notch t, thus positively forcing the 50 movable gripping-jaw downward and insuring a firm grip upon the splicing-thread.

The cam-bar S carries on its outer end a downwardly-projecting tappet-pin T, into the path of which the cam-plate R is brought 55 when the lever Q is lifted. (See Fig. 1.) When the cam-bar S and its tappet-pin T occupy their innermost position, the outer surface of the inner edge of the cam-plate R is in the path of the tappet-pin (see Fig. 2)—that is, when the parts are in this position the inner edge of the cam-plate is nearer the axis of the machine than the tappet-pin.

When, therefore, in its rotation the tappet-pin encounters the cam-plate, it travels on the outer surface thereof, and in this manner the 70 cam-bar S is drawn out, thus lifting the movable gripping-jaw of the gripper and leaving the splicing-thread free to be fed to the needles by the frictional contact therewith of the main thread. The movable jaw of the gripper then remains in the uplifted position for an interval depending upon the desired width of the patch, and while it is so uplifted the knitting with the splicing-thread continues. The movable jaw of the gripper is caused 80 to descend and grip the thread (and so limit the width of the patch) by a stationary inclined cam-plate U, fixed at the desired position on the head-plate, with its cam-face in the plane and path of the tappet-pin T. The 85 coacting face of this cam faces the axis of the machine, so that when the tappet-pin is engaged thereby it forces the tappet-pin radially inward, thus moving in the cam-bar S, and so depressing the gripper, causing the 90 latter to grip the thread, so that it is broken by the onward movement of the dial-plate E. The gripping edge of the movable jaw of the gripper is in close proximity to the leading-in guide-eye in the guide-plate, (see Figs. 4 and 95 7,) so that the broken end of the splicing-thread is always left in the guide-eye, where it is subject to the frictional contact of the main thread the moment the gripper is raised. To insure proper frictional contact, however, 100 it is desirable that the path of the main thread as it enters the leading in guide-eye should approximate that of the splicing-thread, and the last thread-guide eye i on the bracket-arm G, through which the main thread passes, 105 is located with this object in view. As long as the lever Q remains in its elevated position, with the cam-plate R in the path of the gripper-controlling tappet-pin T, the movable jaw of the gripper will be raised and lowered at 110 each round of stitches. When, however, through the instrumentality of the pattern-chain, the inner rod M is lifted, and the lever P is swung so that its projecting tongue q no longer upholds the lever Q, the cam-plate R is lowered below the path of the tappet-pin 115 and no longer co-operates therewith, so that the movable jaw of the gripper constantly occupies its normal lower position, gripping the splicing-thread and rendering it inoperative. 120

There only remains now to be described the construction of the improved splicing-thread slackener and of the parts co-operating therewith, whereby the splicing-thread is relieved of all tension at the moment when the movable jaw of the gripper is lifted, in order that the splicing-thread may with certainty and instantaneously be fed in by the frictional contact therewith of the main thread. This thread-slackener is carried by the dial-plate E or the bracket-arm thereon, and its object is to give down the splicing-thread and leave it slack in a loop and entirely without tension.

The thread-slackener consists, primarily, of a thread-slackening vertically-swinging lever V, which is centrally pivoted on a vertically-extending bracket w, carried by the bracket-arm G, having one end normally uplifted by a spring W. Fastened to the upper and outer end of the thread-slackening lever V is a thread-clasping spring friction-plate X, extending alongside the outer face of the lever 5 and normally held out of contact therewith by its own elasticity. Between the lever V and this thread-clasping friction-plate the splicing-thread extends loosely in passing from the tension-eye h to the gripper, no friction 10 on the thread resulting from this passage. (See Fig. 8.) Alongside the inner free end of the thread-clasping friction-plate X is a double-acting fixed cam Y, rigidly secured to the bracket w, occupying a plane below 15 the normal position of the free end of the thread-clasping friction-plate, and having an inner cam-face a', facing the lever V, and an outer cam-face b'. If, then, the upper end of 20 the thread-slackening lever carrying the thread-clasping friction-plate is lowered by a proper instrumentality, the free inner end of the friction-plate is brought into contact with the inner cam-face a', which forces the friction-plate into frictional contact with the 25 slackening-lever, whereby the splicing-thread is clasped between the said plate and lever. Further movement of the slackening-lever in the same direction draws down the splicing-thread from the upper tension-eye h, and at 30 the same time gives down the portion of the splicing-thread between the thread-clasping friction-plate and the movable gripping-jaw J, thus slackening the splicing-thread. This 35 downward movement continues until the inner free end of the thread-clasping friction-plate passes beneath the cam Y, when the friction-plate springs away from the slackening-lever and thus releases the splicing-thread. The 40 instrumentality which lowers the upper end of the slackening-lever then ceases to act, and the latter is free to be lifted by the spring W. During the upward movement of the outer end of the slackening-lever the inner face of the thread-clasping friction-plate X encounters 45 the outer cam-face b' (see Fig. 8) of the cam Y, thus pressing the friction-plate away from the slackening-lever for the purpose of providing a sufficient space between the friction-plate and the slackening-lever, so that 50 there may be no possibility of the splicing-thread being dragged up, and so losing the slack by the upward movement of the slackening-lever. The upward movement of the outer end of the slackening-lever is sufficient 55 to carry the thread-clasping friction-plate entirely above the cam Y, so that it is left in its normal position.

The spring friction-plate X and the coacting face of the slackening-lever constitute the two 60 members of a splicing-thread clasp, which is normally open, but which, when the slackening-lever moves in one direction, closes and

clasps the splicing-thread, and which again opens and entirely releases the splicing-thread when the slackening-lever moves in the opposite direction. The opening and closing of the splicing-thread clasp thus formed are effected by the cam Y and the resilience of the spring member X of the clasp. 70

From the foregoing description it will be noted that I use the expression "thread-slackener" to designate the slackening-lever V and all the parts carried thereby, and that I use the expression "splicing-thread clasp" to designate those parts carried by and constituting part of the thread-slackener, the function of which is to clasp the splicing-thread during the downward movement of the outer end of the thread-slackener. The function of the thread-slackener is simply to slacken 85 the thread, and the presence of the splicing-thread clasp is to accomplish this function by clasping the splicing-thread, and consequently pulling it positively in a downward direction. 90

The instrumentality for lowering the upper end of the slackening-lever consists in an inclined cam-plate Z, (see Fig. 9,) fixed to the head-plate A, the upper inclined cam-face c' of which is encountered by the tail end of 95 the slackening-lever during the rotary movement thereof. The tail end of the slackening-lever travels up this inclined cam-face, thus lowering the upper end of the slackening-lever in the desired manner. The cam-plate Z should be fixed in such a position that it will be encountered by the slackening-lever after the movable gripping-jaw J has gripped the splicing-thread and before it is raised to release the same. The thread-slackener can be operated to slacken the thread at any time during this interval. It is only essential that the splicing-thread be slackened after the knitting therewith has ceased, so that the slack cannot be taken up 100 by the knitting, and before the gripper releases the splicing-thread, so that the moment the thread is released by the gripper it is slack, without tension, and free to be fed in to the needles by the frictional contact of 115 the main thread therewith. In the drawings the cam-plate Z is shown at the same place on the head-plate as the cam-plate U, which lowers the movable gripping-jaw J; but owing to the angular position of the slackening-lever its tail end does not encounter the cam-plate Z until after the gripper has seized the 120 splicing-thread. 125

An important feature of the construction and operation of the thread-slackener consists 130 in the arrangement whereby its splicing-thread clasp moves to and from the leading-in thread-guide and the splicing-thread gripper in a path approximating that in which the splicing-thread extends in its passage from the tension-eye h to the gripper, so that when the splicing-thread clasp of the thread-slackener clasps the thread the thread-slackener pulls only upon the tension-eye and in

substantially the direction of the path of the thread. (This is shown in Fig. 8 particularly.) There is consequently no strain upon the thread at the gripper, the existence of which 5 might either break off the splicing-thread at the gripper, or else pull the thread out from under the gripper, in either case rendering the splicing-thread inoperative. This movement of the thread-slackener in substantially 10 the plane of the path of the splicing-thread is also specially adapted to the operation of the splicing-thread clasp. This splicing-thread clasp enables the slackener to draw down the splicing-thread directly and positively 15 from the tension-eye, so that the entire slack is formed between the thread-clasp and the gripper. Then when the slackener moves upward toward the tension-eye the thread-clasp releases the thread, so that it does not 20 take up the slack, and as the slackener moves up toward the tension-eye it does not drag against the splicing-thread and thereby cause the slack to be partly taken up.

The mechanism for slackening the splicing-thread and relieving it of tension is thus very 25 simple, consisting only of the slackening-lever, its splicing-thread clasp, and the operating-cams Y and Z.

An important feature of the improved 30 means for gripping and feeding in the splicing-thread is that the splicing-thread can thereby be used with any arrangement of the dial and cylinder needles, no special arrangement thereof being necessary.

35 We claim as our invention—

1. A feeding-in thread-guide of a knitting-machine, through which the splicing-thread passes, in combination with a thread-slackener which moves to and from said thread-guide, said thread-slackener being provided with a splicing-thread clasp which clasps the splicing-thread when the thread-slackener moves toward the thread-guide and releases the splicing-thread when the thread-slackener moves from the thread-guide, and means for closing and opening the clasp upon the splicing-thread as the slackener moves, substantially as set forth.

2. A tension thread-eye and a feeding-in 50 thread-guide, between which and said tension thread-eye the splicing-thread extends, in combination with a thread-slackener which moves between said thread-eye and said thread-guide, said thread-slackener being provided with a splicing-thread clasp which clasps the splicing-thread when said thread-slackener moves toward said thread-guide and releases the splicing-thread when said thread-slackener moves toward said tension 55 thread-eye, and means for closing and opening the clasp upon the splicing-thread as the slackener moves, substantially as set forth.

3. A thread slackener consisting of a swing- 60 ing lever and a thread-clasping friction-plate carried by said lever, said plate and the coacting face of the lever constituting the two

members of a splicing-thread clasp, between which two members the splicing-thread passes, in combination with a cam with which said thread-clasping friction-plate is brought in contact by the movement of the lever, whereby said splicing-thread is clasped between said thread-clasping friction-plate and the coacting face of said lever, substantially as 75 set forth.

4. A thread-slackener consisting of a swinging lever and a thread-clasping spring friction-plate carried by said lever, said plate and the coacting face of the lever constituting the two members of a splicing-thread clasp, between which two members the splicing-thread passes, in combination with a double-faced cam, with the inner face of which said thread-clasping friction-plate is 80 brought in contact when said swinging lever moves in one direction, whereby said thread-clasping friction-plate is pressed against the coacting face of said lever, and with the outer face of which said thread-slackening friction-plate is brought in contact while said lever is being restored to its normal position, whereby said thread-clasping friction-plate is moved away from said lever, substantially as set forth.

5. A feeding-in thread-guide of a knitting-machine through which the splicing-thread passes, and a splicing-thread gripper which alternately grips the splicing-thread to break it off and opens to permit the thread to be fed 100 in to the needles of the knitting-machine, in combination with a thread-slackener for the splicing-thread, which moves to and from said gripper, said thread-slackener having a splicing-thread clasp which clasps said splicing-thread when the thread-slackener moves toward said gripper and releases the splicing-thread when the thread-slackener moves from said gripper, and means for closing and opening the clasp upon the splicing-thread as the 105 slackener moves, substantially as set forth.

6. A feeding-in thread-guide of a knitting-machine through which both the main thread and the splicing-thread pass, and a splicing-thread gripper which releases the splicing- 115 thread when it is being operated upon by the knitting-needles of the knitting-machine, and which grips the splicing-thread during the entire period when it is not being operated upon by the knitting-needles, in combination with 120 a splicing-thread slackener which moves to and from said gripper, said thread-slackener moving toward said gripper while it is gripping the splicing-thread and before it releases said thread, said thread-slackener having a 125 splicing-thread clasp which clasps the splicing-thread when the thread slackener moves toward said gripper and which releases said splicing-thread when the thread-slackener moves from said gripper, and means for closing and opening the clasp upon the splicing-thread as the slackener moves, substantially as set forth.

7. A splicing-thread gripper having fixed

and movable jaws, a movable cam-plate, and intermediate mechanism between said gripper and said cam-plate, whereby when said cam-plate is moved to one position it co-operates with said gripper and when said cam-plate is moved to its other position it is ineffective to control said gripper, in combination with a swinging lever adapted when moved to one position to render said cam-plate operative and when moved to its other position to render said cam-plate inactive, two movable rods acting on said swinging lever to move it in opposite directions, and a pattern-chain controlling the movements of said rods, substantially as set forth.

8. The lever P and the lever Q co-operating therewith, in combination with the rods L M, acting on said lever P to move it in opposite directions, and the pattern-chain co-op-

erating with said rods, substantially as set forth.

9. The stationary gripping-jaw and the movable gripping-jaw co-operating therewith, said movable jaw having a notch *t* therein, in combination with the reciprocating cam-bar S, having cam-faces *u v*, which co-operate with said notch *t* to move said movable jaw positively in opposite directions, substantially as set forth.

In witness whereof we have hereunto signed our names in the presence of two subscribing witnesses.
